STEM FOR PIPES, CIGAR AND CIGARETTE
HOLDERS

Frank C. La Valle, Chicago, Ill.

Application December 4, 1939, Serial No. 307,438

6 Claims. (Cl. 131—229)

This invention relates to stems or mouthpieces for smoking devices or cigar and cigarette holders.

The object of the invention is to provide a novel and desirable construction of mouthpiece or bit for such stems which will properly spread or diffuse the smoke to insure a cool and dry fragrant smoke and prevent the smoke impinging upon one point of the tongue or mouth of the user and burning or biting especially at the tip of the tongue.

Another object of the invention is to facilitate holding the pipe in the mouth between the teeth and to prevent a slug from being drawn into the mouth and throat, as well as to facilitate cleaning of the stem and lip or bit and removal of saliva while allowing the smoke to filter through from the stem passage and to spread the same in the mouth.

Another object is to provide a novel and simple method of producing the stem or mouthpiece from a plastic, such as vulcanized hard rubber to facilitate molding thereof.

Further objects and advantages will appear and be brought out more fully in the following specification, reference being had to the accompanying drawing, in which—

Fig. 1 is a side elevation of a smokers article illustrated as a pipe with the stem thereof in section;

Fig. 2 is an enlarged side sectional elevation of the stem or mouthpiece;

Fig. 3 is an enlarged end view of the mouthpiece end;

Fig. 4 is a section on the line 4—4 of Fig. 3;

Fig. 5 is a section on the line 5—5 of Fig. 4;

Fig. 6 is a view similar to Fig. 3 of another form; and

Fig. 7 is a section taken on the line 7—7 of Fig. 6.

Referring more particularly to the drawing, the invention has application to smokers' articles such as a pipe or holder for cigars and cigarettes, but by way of illustration in Figs. 1 and 2 is shown as a stem for a pipe. However, its application and the forms shown in Figs. 4 and 7 are applicable to cigar or cigarette holders. As shown, 10 designates a tobacco pipe having a bowl 11 and a stem 12 in the form of an extension of the bowl. The mouthpiece or stem proper is designated at 13 and the extension 12 is shown provided with a socket or bore 14, preferably tapered to receive a reduced tapered portion 15 at the enlarged end of the tapered oval mouthpiece 13, so as to align the bore or smoke passage 16 of the ex-

tension with the bore or smoke passage 17 through the stem or mouthpiece 13 which may be tapered as shown.

The small end of the mouthpiece 13 is provided with an enlargement in the form of an oval biteless lip or bit 18 which may be integral as shown, projecting above and below the top and bottom of the mouthpiece at the front to provide a top shoulder 19 and a bottom shoulder 20 both extending substantially vertically or at right angles 10 to the top and bottom faces of the mouthpiece to facilitate gripping or holding the device between the teeth and lips. The stem, while shown and described as being of oval cross section and considerably wider horizontally than it is thick vertically, may be of any suitable shape and is preferably of vulcanized hard rubber or other plastic material which may be molded to any desired shape or size.

The enlargement forming the bit or lip portion 18 which may be oval lengthwise thereof or transversely of the mouthpiece, stem or holder tapers in opposite directions and is provided with a transverse passage 21 below the vertical center thereof and of relatively small area or cross-section compared to the bit 18 intersecting the small end of the tapered bore or smoke passage 17 which extends into the bit 18 and extending equidistantly on opposite sides thereof to form a tubular bit with the passage 21 of substantially 30 uniform diameter throughout its length and freely open at the ends and preferably with the bore 17 of the stem extending substantially tangentially thereto. In Fig. 4 of the drawing the small end of the tapered passage 17 in the bit 18 35 is above communicates with and is tangential to the top or above the median line of the opening or passage 21 at the bottom of the passage 17 as shown at 22 so that any saliva, nicotine, particles of tobacco or a slug will drain from the passage 40 17 into the bore or passage 21 extending from end to end through the bit substantially at right angles to the passage 17 and saliva in the mouth will be prevented from normally entering the passage 17 to the tobacco or pipe bowl, or to a 45 cigar or cigarette.

The back or exposed end of the bit 18 is provided with a series of narrow slots 23 extending up and down and preferably arranged in parallel series, their direction being substantially upright 50 and forming intermediate and end baffle walls 24. Any number of such slots may be provided and as shown in Figs. 3 and 4 they are arranged in opposite series on opposite sides of the central bore or passage 17 extending substantially up- 55

right, but slightly inclined in opposite directions toward each other at the bottom from their upper ends to their lower ends with the inner walls thereof undercut or inclined from the back face 5 of the bit forwardly to partially intersect the passage 21, as seen especially in Fig. 4. The oppositely inclined parallel series of slots on each side of the center or passage 17 preferably extending from a distance part way down on the 10 back face of the bit 18, such as one-third way down communicate with the bore or passage 21 are undercut, diverge upwardly on opposite sides of the bore or passage 17 and produce an intermediate or center baffle wall 25 at and extending 15 across the back end of the passage 17 including the projected area thereof or in line with the bore or passage 17 tapering downwardly in the same direction as the opposite slots converge toward each other. This wall is located in back of the 20 passage 17 and prevents the smoke from being drawn straight through to impinge against the tongue and causing a biting effect of the tongue, lips or cheeks which would ordinarily result in soreness. By reason of the baffle walls 24 and 25 the wall 25, the smoke will be spread in opposite directions and caused to take a tortuous path out through the ends of the tubular bit or horizontal transverse passage 21 and also pass through the upright slots 23, thus preventing a direct draft 30 and serving to spread or divide the smoke into spaced vertical or upright streams so that the same will be maintained dry and cool as well as preventing moisture, nicotine or particles of tobacco entering the mouth or saliva in the mouth 35 from entering the passage 17 and tobacco in the pipe bowl or holder. Moreover, a proper draft is insured as most of the openings will remain open and unobstructed as compared with a single passage ordinarily provided. It is, of course, to be understood that the stem part, instead of being made to fit a pipe may be made to receive a cigar or cigarette in the case of holders for such articles.

In the form shown in Figs. 6 and 7 of the drawing, the passage 17 enters the passage 21 slightly below the top thereof as indicated at 26 with the top of passage 17 tangential to the top of the passage 21, both arrangements having the passage 17 substantially tangentially to the passage 50 21 either at the periphery or below the same, that is, within the wall thereof. In this case the slots may be arranged as shown in Figs. 3, 4 and 5, or any other suitable spaced relation vertically, upright or inclined, but are shown as slots 27 arranged on opposite sides of the passage 17, but inclined in one or the same direction parallel to each other although they may converge if desired. This provides baffle walls 28 between the slots and an intermediate or central wall 29 corresponding to the walls 24 and 25 for the same purposes as heretofore described.

In accordance with the method of producing the stem or mouthpiece, the same is made of a suitable molded plastic such as vulcanized hard 65 rubber or the like, although it may be of Bakelite or other suitable nonbreakable material. The plastic in a soft condition is placed in a suitable mold and cores are provided for the passages 17 and 21 in the same relation that these passages 70 are to be finally formed, such as shown in Figs. 4 and 7 of the drawing. A tapered core forms the passage 17 and a cylindrical core forms the passage 21 so that the latter will extend through the ends of bit 18 which is also formed at the same time in the mold. In the form shown in Fig. 4,

the core of the passage 17 contacts or is engaged on the periphery of the core which forms the passage 21 and in the form shown in Fig. 7 the core of the passage 17 is curved to fit the core of the passage 21 corresponding to the wall or peripheral line of the passage 21 or the core therein so that the end of the core in the passage 17 will be concaved to bring the passage 17 lower down at its point of communication with the passage 21 at the closed end in the bit 18 formed by the 10 wall 25. By this means, the mouthpiece or stem may be made for a pipe or as a holder for cigar or cigarette with facility. In each case, the smoke will pass into the mouth as heretofore described and at the same time it will prevent a slug of tobacco or nicotine, or particles being drawn into the mouth, as well as insuring a cool dry smoke instead of burning the tongue or mouth, by spreading the smoke into various narrow spaced vertical streams in the manner described. However, the slots may be readily cleaned, if found necessary, and an ordinary pipe cleaner may be inserted through the passage 17 as well as the transverse passage 21 for cleaning the same.

While I have illustrated and described the preferred form of construction for carrying my invention into effect, this is capable of variation and modification without departing from the spirit of the invention. I, therefore, do not wish to be limited to the precise details of construction set 20 forth, but desire to avail myself of such variation and modifications as come within the scope of the appended claims.

Having thus described my invention, what I claim as new and desire to secure by Letters 25 Patent is:

1. A stem for tobacco pipes, cigar or cigarette holders having a bore and provided with a tubular bit transversely at the mouth end of the stem, having a transverse bore communicating with the 40 bore of the stem, extending substantially tangentially thereto and slots extending up and down in the mouth end of the bit and intersecting the transverse bore.

2. A mouthpiece for smokers articles having a 45 bit provided with a transverse passage open at the ends thereof and a bore longitudinally and communicating with said passage at the top only of the latter, the transverse passage being closed at the back of the bit in the projected area of the 50 bore.

3. A stem for tobacco pipes, cigar or cigarette holders having a bore and provided with a tubular bit transversely at the mouth end of the stem, the bore of the stem extending substantially tangentially thereto, said bit having front shoulders at the top and bottom and a wall extending across the bit end of the bore in line therewith, and slots extending up and down at the back of the bit and communicating with the bore thereof. 60

4. A mouthpiece for smokers articles having a bit provided with a transverse passage open at the ends thereof and a bore longitudinally and communicating with said passage at the top of the latter, the mouthpiece having a central wall 65 in back of the bore where it communicates with the passage and spaced oppositely inclined rectilinear slots on opposite sides thereof extending into the passage, the slots on opposite sides converging toward each other. 70

5. A mouthpiece for smokers articles having a bit provided with a transverse passage open at the ends thereof and a bore longitudinally and communicating with said passage at the top portion only of the latter, the mouthpiece having an im- 75

perforate top wall and a wall in back of the bore where it communicates with the passage and spaced converging slots in the lower portion of the bit inclined forwardly under the passage and communicating therewith.

5 6. A mouthpiece of the class described, comprising a stem with a longitudinal passage and an

enlarged bit with a transverse passage communicating with the longitudinal passage, the bit having a solid wall at the back across the top portion thereof and undercut slots at the bottom extending up and down and intersecting the transverse passage.
